UNITED STATES PATENT OFFICE.

GEORGE R. NETTLETON, OF NEW HAVEN, CONNECTICUT, ASSIGNOR TO THE W. & E. T. FITCH CO., OF NEW HAVEN, CONNECTICUT, A CORPORATION.

BUCKLE.

1,178,024.

Specification of Letters Patent.

Patented Apr. 4, 1916.

Application filed October 11, 1915. Serial No. 55,207.

To all whom it may concern:

Be it known that I, GEORGE R. NETTLETON, a citizen of the United States, residing at New Haven, in the county of New Haven 5 and State of Connecticut, have invented a new and useful Improvement in Buckles; and I do hereby declare the following, when taken in connection with the accompanying drawings and the characters of reference 10 marked thereon, to be a full, clear, and exact description of the same, and which said drawings constitute part of this application, and represent, in—

Figure 1 a top or plan view of a buckle 15 constructed in accordance with my invention. Fig. 2 a side view of the same. Fig. 3 an inside view. Fig. 4 a front view. Fig. 5 a sectional view showing a strap engaged with it.

20 This invention relates to an improvement in buckles, and while adapted for various purposes, is especially designed for use in connection with belts on harvesters, the object of the invention being to produce a 25 buckle which is, in a sense, so flexible that it will readily yield to the various positions of the strap or web with which it is connected; and the invention consists in the construction hereinafter described and par- 30 ticularly recited in the claims.

In carrying out my invention, I employ a frame-plate 2 formed at its forward edge with teeth or serrations 3, and on opposite sides at its forward edge with outwardly 35 projecting wings 4 and 5, and on opposite sides with downwardly extending ears 6 and 7. Each ear has two perforations to receive the bars 8 and 9 of loops 10 and 11, whereby the loops are pivotally connected with 40 the frame. The front bar 12 of the forward loop 11 extends slightly beyond the forward edge of the plate and so as to co-act with the teeth thereon to grip a web 13. The wings

on opposite sides limit the upward movement of the bar and prevent the forward 45 edge of the bar passing over the gripping edge. The bars 8, 9, are parallel and together form a bar to which the fixed end 15 of the web or strap is attached. The rear bar 14 of the loop 10 projects for a considerable 50 extent beyond and above the rear edge of the frame plate and forms a tuck loop for the free end of the strap, as shown in Fig. 5 of the drawings. By loosely pivoting the loops in the frame they may swing with relation 55 thereto so as to respond to the various lines of draft placed upon the strap, at the same time forming a tight grip upon the free end of the strap, and because the point of fixed attachment is so close to the gripping point 60 the fixed buckle will readily adjust itself and permit the strap or web to pass over rollers.

I claim:

1. A buckle comprising a frame plate, a 65 forward loop and a tuck loop, said frame formed on opposite sides with downwardly extending perforated ears in which the loops are mounted, means below the frame plate to which the strap may be connected, the tuck 70 loop projecting beyond and adapted to extend above the rear edge of the plate.

2. A buckle comprising a frame plate, a forward loop and a tuck loop, said plate formed on opposite sides with outwardly ex- 75 tends wings adapted to bear upon the sides of the forward loop, said plate also formed on opposite sides with downwardly extending perforated ears through which the adjacent bars of the loops pass, said ad- 80 jacent bars forming a strap-attaching bar, the forward loop adapted to co-act with the gripping edge of the plate, and the tuck loop projecting beyond and adapted to extend above the rear edge of the plate.

GEORGE R. NETTLETON.

Copies of this patent may be obtained for five cents each, by addressing the "Commissioner of Patents, Washington, D. C."
